90,867

DESIGN FOR A COMBINED RADIOCABINET AND RADIO RECEIVING SET

Francis E. Billings, New York, N. Y.

Application May 16, 1933. Serial No. 48,128

Term of patent 3½ years

● *To all whom it may concern:*

Be it known that I, FRANCIS E. BILLINGS, a citizen of the United States, residing at New York, in the county of New York and State of New York, have invented a new, original, and ornamental Design for a Combined Radiocabinet and Radio Receiving Set, of which the following is a specification, reference being had to accompany drawing, forming part thereof.

Figure 1 is a view showing a front elevation of a combined radiocabinet and radio receiving set, showing my new design.

Figure 2 is a plan view.

Figure 3 is an end elevation.

In the drawing the cabinet is shown as it would be made wherein the general design represents a bar with a rail at the lower edge and a moulding forming a border around the upper edge. The front of the cabinet is formed with panels, and knobs of a radio receiving set are positioned in the panels.

I claim:

The ornamental design for a combined radiocabinet and radio receiving set as shown and described.

In testimony whereof I affix my signature.

FRANCIS E. BILLINGS.
